UNITED STATES PATENT OFFICE.

EDDIE P. TRUESDALE, OF CAMDEN, SOUTH CAROLINA.

RAZOR ATTACHMENT.

980,027.

Specification of Letters Patent. Patented Dec. 27, 1910.

Application filed May 19, 1910. Serial No. 562,235.

To all whom it may concern:

Be it known that I, EDDIE P. TRUESDALE, a citizen of the United States of America, residing at Camden, in the county of Ker-
shaw and State of South Carolina, have invented certain new and useful Improve-
ments in Razor Attachments, of which the following is a specification, reference being had therein to the accompanying drawing.
10 This invention relates to guards for razor blades, and the principal object of the same is to provide a guard for the razor blade which permits the blade to be used without danger of cutting the user and in which the
15 blade may be adjusted to present the cutting edge at the desired angle for shaving.

In carrying out the objects of the invention generally stated above it will be understood, of course, that the essential features 20 thereof are necessarily susceptible of changes in details and structural arrangements, one preferred and practical embodiment of which is shown in the accompanying drawings, wherein:—

25 Figure 1 is a perspective view of a razor the blade of which is equipped with the improved guard. Fig. 2 is a detail perspective view of the guard. Fig. 3 is a transverse sectional view taken on the line 3—3,
30 Fig. 1. Fig. 4 is a similar view taken on the line 4—4, Fig. 1.

The improved guard forming the subject-matter of this invention is especially adapted for use in connection with the well known 35 type of razors wherein the blade is hinged to a handle.

Referring to the accompanying drawings by numerals, it will be seen that the improved guard comprises a flat plate 1 that 40 forms a rest for the blade 2 of a razor, said rest being slightly concaved and having an upstanding wall 3 at one longitudinal edge that is concaved to provide a holding and guiding groove for the back of the razor 45 blade. The upper portion of said wall has the flanges 4 projecting therefrom, said flanges being resilient and adapted to yield-
ably engage the blade. A neck 5 projects laterally from the wall 3 between said 50 flanges 4, said neck connecting with a plate 6 having a flanged longitudinal edge 7 that is provided with comb teeth 8.

The structure as described is preferably an integral one and may be formed of steel or sheet metal. Said structure provides a 55 rest for one side of the blade, gripping flanges which yieldably bear upon the other side of the blade to retain the same resting on the said plate and the back thereof is the grooved wall 3, a plate 6 for shielding the 60 upper side of the cutting edge of the blade, and the teeth 8 which project across the cutting edge in spaced relation. And, as will be clear, the guard is so constructed that the blade may be readily slid therein or 65 removed therefrom.

The neck 5 is provided with a central boss 9 through which a threaded opening is formed for the reception of a thumb screw 10 which may be manipulated therein to 70 cause its free end to contact with the blade and force the plate 6 away from the blade, thereby causing the teeth 8 to move to a higher plane than the cutting edge of the blade, so that said blade can be used at an 75 angle to the surface being shaved. Obviously, a reverse movement of the screw 10 removes the same from binding contact with the blade, and the resiliency of the plate 6 returns the comb teeth to their original 80 position.

What I claim as my invention is:—

A safety attachment for a razor blade formed from spring metal comprising a longitudinal blade rest, a flange formed 85 upon one side of said rest, a pair of end flanges formed upon the other side of said rest and adapted to clamp said blade between said side flanges, a depending tongue formed between said pair of end flanges, 90 a longitudinal plate formed at the lower end of said tongue, and provided with a series of comb teeth, and a set screw passing through said tongue and contacting with the 95 razor blade to adjust said plate.

In testimony whereof I hereunto affix my signature in presence of two witnesses.

EDDIE P. TRUESDALE.
